J. B. MENZL

WRENCH

Filed Feb. 15, 1922

Inventor
JOHN B. MENZL.

By *General Reed*

Attorney

UNITED STATES PATENT OFFICE.

JOHN B. MENZL, OF DAYTON, OHIO.

WRENCH.

Application filed February 15, 1922. Serial No. 536,615.

To all whom it may concern:

Be it known that I, JOHN B. MENZL, a citizen of the United States, residing at Dayton, in the county of Montgomery and State of Ohio, have invented certain new and useful Improvements in Wrenches, of which the following is a specification, reference being had therein to the accompanying drawing.

10 This invention relates to a wrench and one object of the invention is to provide a wrench in which the jaws will yield to permit the wrench to be moved in a reverse direction over the corners of the nut.

15 A further object of the invention is to provide such a wrench which will be adjustable to accommodate it to nuts of different sizes.

20 A further object of the invention is to provide an open end wrench of this kind which will be of a strong, durable character.

Other objects will appear as the device is described in detail.

In the accompanying drawings Fig. 1 is 25 a side elevation of a wrench embodying my invention, showing the jaws in their gripping positions; Fig. 2 is a similar view showing the jaws separated to pass the corners of the nut; Fig. 3 is a section taken 30 on the line 3—3 of Fig. 1; Fig. 4 is a section taken on the line 4—4 of Fig. 1; Fig. 5 is a section taken on the line 5—5 of Fig. 1; Fig. 6 is an end elevation of the wrench; and Fig. 7 is a side elevation of a slightly 35 modified form of the wrench.

In these drawings I have illustrated one embodiment of my invention and have shown the same as comprising a handle 1 having pivotally mounted thereon a jaw 2.

40 The pivotal connection between the jaw and the handle may be established in various ways but, as here shown, that end of the handle adjacent to the jaw is slotted, as shown at 3, and the corner thereof is rounded to form 45 a bearing surface. The adjacent portion of the jaw structure is recessed, as shown at 4, and the recess has a rounded corner to form a bearing surface to cooperate with the rounded bearing surface on the handle.

50 Extending inwardly from the walls of the recess and spaced from both edges thereof is a lug, or web, 5 which enters the slot 3 in the handle and is secured therein by a pivot pin 6. The walls of the recess 4 of the jaw structure diverge at a greater angle than do the edges of the end portion of the

handle, thus permitting of the relative movement of the jaw and the handle about the pivot pin 6. A spring pressed plunger 7 engages one wall of the recess and tends to hold the jaw normally in its operative, or gripping, position and when in this position the other wall of the recess, as shown at 8, will engage the adjacent part of the handle, and form a rigid stop to limit the pivotal movement of the jaw. This plunger, however, will permit the jaw to yield when pressure is applied thereto and will restore it to its normal position as soon as that pressure is relieved.

70 A second jaw 9 is mounted for movement toward and from the first mentioned jaw and this movement is controlled by a device which in turn is controlled by the pivotal movement of the first mentioned jaw. As here shown, the jaw 9 is slidably mounted on and is carried by the pivoted jaw so that it will move therewith about the axis of the pivoted jaw. To this end the slidable jaw is provided with an arm, or 75 slide bar, 10 which is slidably mounted in a guideway 11 in the pivoted jaw. Preferably the slidable jaw is provided on its outer side with an inclined bearing surface and, as here shown, the outer portion 80 12 of the slidable jaw is cut away on both sides to provide shoulders 13, which are inclined inwardly and toward the handle 1. Cooperating with the shoulders on the slidable jaw is a suitable stop which is so 85 mounted that it will not move with the jaws about the axis 6 and, consequently, when the jaws are moved about that axis the position of the slidable jaw with relation to the stop will be altered and because of the inclined 90 surfaces the outer limit of movement of that jaw will be varied. In the present construction I have mounted the stop upon the pivoted jaw and to that end the pivoted jaw is provided with a forwardly extending portion 95 100 14 provided in each side with a guideway 15 and the stop is in the form of a bifurcated block 16 the two parts of which are slidably mounted in the respective guideways 15. I also prefer that this block shall 105 have that end adjacent to the slidable jaw inclined as shown at 17 to correspond with the inclination of the shoulders 13 on the slidable jaw. The inclined ends of the two parts of the stop overlap the inclined 110 shoulders of the jaw and form a positive stop to limit the outward movement of that

jaw, that is, to limit the movement of the slidable jaw away from the pivoted jaw.

Obviously, the amount of movement which may be imparted to the slidable jaw is determined by the relative positions of the inclined surfaces of the stop and the jaw. The stop is held against movement with the jaws about the pivot pin 6, and to this end I have connected the stop with the handle 1 in such a manner as to hold it against movement lengthwise of the handle but permit it to accommodate itself to the changed positions of the guideways 15 due to the movement of the pivoted jaw about its axis. As shown in Figs. 1 and 2, this connection is accomplished by a connecting device comprising a member 18 pivotally mounted on a lug 19 carried by the stop and having its other end rotatably mounted in a socket 20 formed in a head 21 having a shank 22 which is screw threaded into a trunnion 23 journaled in the handle. That portion of the member 18 which extends into the socket 20 is provided with a circumferential groove 24 and a pin 25 is mounted in the wall of the socket and extends into the groove to hold the member 18 in the socket, but to permit the relative rotation of the two parts. It will be apparent that the rotation of the head 21 will cause the connecting device and the stop 16 to move toward or from the slidable jaw, thus altering the relative positions of the inclined surfaces of the jaw and the stop and changing the limit of movement of the jaw. In this manner the wrench may be accommodated to nuts of different sizes. When the wrench has been placed upon a nut and the handle is moved in a forward direction, that is, downward in Figs. 1 and 2, the jaws will grip the faces of the nut and as the pressure of the handle is against the wall 8 of the pivoted jaw there is no tendency for the jaw to move about its axis and the outward movement of the slidable jaw being prevented by the stop 16, it will be apparent that the nut will be very firmly gripped between the jaws and may be rotated by the wrench. When the handle is moved in a rearward direction, that is, upwardly in Figs. 1 and 2, the pivoted jaw will move about its axis, thus carrying the slidable jaw upwardly and away from the stop 16 and permitting the two jaws to be separated an increased distance sufficient to enable them to ride over the corners of the nut, as shown in Fig. 2. As soon as the jaws have passed the corners of the nut they will be restored to their normal positions by the action of the spring pressed plunger 7 and will take a fresh grip on the nut when the handle is again moved forwardly.

When the wrench is designed for use on nuts of a single size only the adjustable feature may be eliminated and the wrench

shown in Fig. 7 is designed for this purpose. As there shown, the wrench corresponds in construction with that above described, with the exception that the stop, shown at 26 in Fig. 7, is of an increased length and is provided in its end portion with a transverse socket 27 to receive the rounded head 28 of a stud 29 carried by the handle. The stop is capable of both a pivotal and a sliding movement relatively to the stud and, consequently, is free to accommodate itself to the changed positions of the guideways in the pivoted jaw when the latter is moved about its axis.

The operation of the device will be readily understood from the foregoing description of the several parts thereof and it will be apparent that I have provided an open end wrench, the jaws of which will yield to permit the same to be moved from one position to another on the nut without removing the wrench from the nut, thereby greatly facilitating the tightening up of the nut. Further, it will be apparent that the wrench is of a very strong, durable character and that the parts thereof are so constructed that they are not liable to breakage or disarrangement. Further, the wrench is adjustable so that it may be accommodated to nuts of different sizes.

While I have shown and described one embodiment of my invention I wish it to be understood that I do not desire to be limited to the details therof as various modifications may occur to a person skilled in the art.

Having now fully described my invention what I claim as new and desire to secure by Letters Patent, is:

1. In a wrench, a handle for supporting and manipulating said wrench, a jaw pivotally mounted on said handle, a second jaw movable toward and from the said pivoted jaw, and a device movable relatively to said handle and controlled by the relative movement of the pivoted jaw and the handle to control the movement of said second jaw.

2. In a wrench, a handle for supporting and manipulating said wrench, a jaw pivotally mounted on said handle, a second jaw movably mounted on the pivoted jaw and movable therewith about its axis, and a device movable relatively to said handle and controlled by the relative movement of said jaw and said handle to control the movement of said second jaw relatively to said pivoted jaw.

3. In a wrench, a handle, a jaw pivotally mounted on said handle, a second jaw movably mounted on the pivoted jaw and movable therewith about its axis, and a part connected with said handle and held against movement with said pivoted jaw to control the movement of said second jaw, one of said parts having an inclined surface so ar-

ranged that the movement of the second jaw, about the axis of the pivoted jaw, will vary the movement which may be imparted to said second jaw relatively to the fixed 5 jaw.

4. In a wrench, a handle, a jaw pivotally mounted on said handle, a second jaw movably mounted on the pivoted jaw and movable therewith about its axis, said pivoted 10 jaw having a part extending beyond the face thereof, a stop movably mounted on said part of said pivoted jaw, having an inclined face to engage said second jaw and connected with said handle.

15 5. In a wrench, a handle, a jaw pivotally mounted on said handle, a second jaw slidably mounted on the pivoted jaw and movable therewith about its axis, said pivoted jaw having a part extending beyond the face 20 thereof, a stop movably mounted on said part of said pivoted jaw, having an inclined face to engage said slidable jaw, and pivotally connected with said handle.

6. In a wrench, a handle, a jaw pivotally 25 mounted on said handle, a second jaw movably mounted on the pivoted jaw and movable therewith about its axis, said pivoted jaw having a part extending beyond the face thereof, a stop movably mounted on said 30 part of said pivoted jaw, having an inclined face to engage said jaw, and adjustably connected with said handle.

7. In a wrench, a handle, a jaw pivotally 35 mounted on said handle, a second jaw slidably mounted on the pivoted jaw and movable therewith about its axis, said pivoted jaw having a part extending beyond the face thereof, a stop movably mounted on said part of said pivoted jaw, having an inclined face to engage said slidable jaw, and pivotally and adjustably connected with 40 said handle.

8. In a wrench, a handle, a jaw pivotally 45 mounted on said handle and having a part extending beyond the face thereof, a second jaw movably mounted on said pivoted jaw and movable therewith about its axis, said second jaw having on its outer side an inclined surface, a stop movably mounted on 50 said part of said pivoted jaw and having an inclined surface to cooperate with the inclined surface of said second jaw, and means for connecting said stop with said handle to prevent its movement with said pivoted jaw.

55 9. In a wrench, a handle, a jaw pivotally mounted on said handle and having a part extending beyond the face thereof, a second jaw slidably mounted on said pivoted jaw and movable therewith about its axis, said 60 slidable jaw having on its outer side an inclined surface, a stop movably mounted on said part of said pivoted jaw and having an inclined surface to cooperate with the inclined surface of said slidable jaw, and 65 means for connecting said stop with said

handle to prevent its movement with said pivoted jaw, and yieldable means acting on said pivoted jaw to retain the same in its normal position.

10. In a wrench, a handle, a jaw pivotally 70 mounted on said handle, a second jaw movably mounted on the pivoted jaw and movable therewith about its axis, means controlled by the relative movement of said pivoted jaw and said handle to control the 75 movement of said second jaw relative to said pivoted jaw, and yieldable means acting on said pivoted jaw to retain the same in its normal position.

11. In a wrench, a handle, a jaw pivotally 80 mounted on said handle and having a part projecting beyond the face thereof and provided at each side thereof with a guideway arranged substantially parallel with the face of the jaw, a second jaw slidably 85 mounted on said pivoted jaw for movement toward and from the same, and movable with said pivoted jaw about its axis, said slidable jaw having bearing surfaces on the outer face thereof, a stop comprising parts 90 slidably mounted in said guideways and having inclined surfaces to engage the bearing surfaces of said slidable jaw, said parts being rigidly connected one to the other, and means for connecting said parts with 95 said handle.

12. In a wrench, a handle, a jaw pivotally 100 mounted on said handle and having a part projecting beyond the face thereof and provided at each side thereof with a guideway arranged substantially parallel with the face of the jaw, a second jaw slidably 105 mounted on said pivoted jaw for movement toward and from the same, and movable with said pivoted jaw about its axis, said slidable jaw having bearing surfaces on the outer side thereof, a stop comprising parts 110 slidably mounted in said guideways and having inclined surfaces to engage the bearing surface of said slidable jaw, said parts being rigidly connected one to the other, and a connecting device pivotally connected with said stop and pivotally connected with said handle.

13. In a wrench, a handle, a jaw pivotally 115 mounted on said handle and having a part projecting beyond the face thereof and provided at each side thereof with a guideway arranged substantially parallel with the face of the jaw, a second jaw slidably 120 mounted on said pivoted jaw for movement toward and from the same, and movable with said pivoted jaw about its axis, said slidable jaw having bearing surfaces on the outer side thereof, a stop comprising parts 125 slidably mounted in said guideways and having inclined surfaces to engage the bearing surface of said slidable jaw, said parts being rigidly connected one to the other, a device pivotally connected with said stop 130

and comprising a rotatable part having screw threaded connection with said handle.

14. In a wrench, a handle, a jaw pivotally mounted on said handle and having a part projecting beyond the face thereof and provided at each side thereof with a guideway arranged substantially parallel with the face of the jaw, a second jaw slidably mounted on said pivoted jaw for movement 10 toward and from the same, and movable with said pivoted jaw about its axis, said slidable jaw having bearing surfaces on the outer side thereof, a stop comprising parts slidably mounted in said guideways and having inclined surfaces to engage the bearing surface of said slidable jaw, said parts being rigidly connected one to the other, a connecting device comprising a part pivotally connected with said stop, a second part 15 rotatably mounted on the first mentioned part and having a screw threaded shank, a trunnion journaled in said handle and having a screw threaded socket to receive said shank.
15. In a wrench of the character described, a handle having one corner slotted and rounded to form a bearing surface, a jaw structure having a rounded recess to re-

ceive the rounded corner of said handle and having a lug adapted to enter the slot in 30 said handle, a pivot pin to secure said lug in said slot, the walls of said recess being arranged to permit said jaw to have movement relatively to said handle about said pivot pin and one wall of said recess acting 35 as a stop to limit the relative movement of the handle and the jaw, said jaw structure also having a part extending beyond the face of said jaw and provided in its opposite sides with guideways, a second jaw slidably mounted on said pivoted jaw for movement toward and from the same and movable therewith about the axis of said pivot pin, said slidable jaw having on its outer 40 side inclined bearing surfaces, a stop comprising parts slidably mounted in said guideways and having inclined surfaces to cooperate with the inclined surfaces of said 45 slidable jaw, and a connection between said stop and said handle to hold the stop against movement with said pivoted jaw structure when the latter moves about its 50 axis.

In testimony whereof, I affix my signature hereto.

JOHN B. MENZL.
